UNITED STATES PATENT OFFICE.

DAVID HENRY ELKINS, OF AMESBURY, MASSACHUSETTS.

DESIGN FOR AN AUTOMOBILE-LAMP DOOR.

51,478.

Specification for Design.

Patented Nov. 13, 1917.

Application filed March 14, 1917. Serial No. 154,881. Term of patent 7 years.

To all whom it may concern:

Be it known that I, DAVID H. ELKINS, a citizen of the United States, residing at Amesbury, in the county of Essex and State of Massachusetts, have invented a new, original, and ornamental Design for Automobile-Lamp Doors, of which the following is a specification, reference being had to the accompanying drawing, forming part thereof.

The figure is a view in front elevation of an automobile lamp door, showing my new design.

I claim:

The ornamental design for an automobile lamp door, substantially as shown.

DAVID HENRY ELKINS.
